UNITED STATES PATENT OFFICE

OTTO LESTER INGWERSEN, OF WAYNE, NEBRASKA

WINDOW VENTILATOR

Application filed October 7, 1929. Serial No. 398,054.

The present invention relates to ventilators, and has for an object the construction of a ventilator which may be incorporated in the construction of a storm sash whereby the interior of a house may be ventilated from time to time without removing the storm sash.

Another object of the present invention is to provide a construction of ventilator 10 which may be incorporated in a storm sash without materially altering the structure of the storm sash, and wherein the ventilator does not add to any appreciable extent to the thickness of the storm sash, nor does it 15 change the appearance of the storm sash to any appreciable extent.

Another object of this invention is to provide a ventilator of this character which may be incorporated in a storm sash having 20 a number of panes, and wherein the ventilator may be mounted in the storm sash either at one side or centrally thereof, and wherein the ventilator is easy of access so that it may be adjusted to different heights 25 so as to ventilate the enclosure as desired.

The invention also aims to provide a ventilator structure for application to a storm sash or the like wherein the center rails of the sash are not disturbed, and wherein 30 the ventilator structure embodies certain filler-in stop strips adapted to fit into the rabbets and other parts of the storm sash for supplying supplementary stop strips to support the ventilator sash.

The above, and various other objects and advantages of this invention will in part be described in, and in part be understood from, the following detailed description of the present preferred embodiments, the 40 same being illustrated in the accompanying drawing, wherein:

Figure 1 is an inner side elevation of a storm sash having the ventilator of this invention applied thereto and showing the 45 ventilator at one side of the sash.

Figure 2 is a similar view of a modified form of storm sash, and illustrating the ventilator as applied to the central portion thereof.

Figure 3 is a horizontal section taken

through the lower portion of the storm sash with the ventilator, substantially on the line 3—3 of Figure 1.

Figure 4 is a similar view taken on the line 4—4 of Figure 2.

Figure 5 is a fragmentary enlarged inner side elevation, partly in section, of the ventilator and sash shown in Figure 1 and with the ventilator partly raised.

Figure 6 is a fragmentary view of the 60 same, showing the upper portion of the horizontal central rail of the sash and with the ventilator in fully raised position.

Figure 7 is an enlarged horizontal section taken through the sash and the ventilator 65 substantially on the line 7—7 of Figure 5.

Figure 8 is a similar view taken substantially on the line 8—8 of Figure 1.

Figure 9 is a detail perspective view of the ventilator sash removed from the storm 70 sash, and

Figure 10 is a fragmentary vertical section taken through the storm sash, substantially on the line 10—10 of Figure 1.

Referring now to the drawings, and first 75 to the construction shown in Figure 1, 10 and 11 designate the side rails, and 12 and 13 designate the top and bottom rails forming the frame of a storm window or sash of usual construction. The frame is provided 80 with horizontal sash bars 14 and one or more vertical sash bars 15, depending upon the number of panes 16 of glass with which the storm window is provided.

The ventilator of this invention comprises 85 a small sliding frame 17 of substantially the dimensions of one of the panes 16, and is adapted to take the place of one of the panes 16, as shown in the drawings.

The frame 17 carries therein a pane of 90 glass 18 which may be one of the panes 16 cut down to fit in the sliding frame 17. The frame 17 is of a width slightly less than the width of the opening between the vertical side rail 11 and sash bar 15 as shown 95 in Figure 1, or between the sash bars 15 in Figure 2 of the storm sash in which the ventilator is fitted. A supplemental parting strip 19 is fitted along each lateral edge 100 of the frame 17 and is shaped to the con-

figuration of the adjacent vertical sash bar 15 and sash rail 11 and is provided with the usual overhanging flange for engaging the outer face of the sliding frame 17 for holding the same in the storm sash. The vertical sash bar 15 is of the usual construction and provided with a stop shoulder 20 against which the pane 16 is usually seated, and which in the present instance provides a support for an outer stop strip 21 which is secured to the vertical sash bar 15 or the like, as shown in Figure 7, and which overlaps the outer side of the ventilator frame 17.

15 The stop strips 19 and 21 therefor provide a guide or runway for holding the ventilator frame 17 in the plane of the storm window. It will be noted from Figure 10 that the outside stop strips 21 terminate at their 20 upper ends against the lower edge of the upper pane 16 so as to support the pane 16 in the upper portion of the window and to also provide means for holding the outer side of the ventilator frame 17 flush with 25 the inner side of the pane 16. The pane 16 provides a stop strip or support for the ventilator window 17 when the latter is raised above the ventilating opening through the storm sash. By use of these 30 inner and outer stop strips 19 and 21, it is unnecessary to change the configuration or construction of the storm window and the device is practically an attachment which may be applied by merely removing one of 35 the panes 16. The inner stop strip 19 may be provided upon its top portion, as shown in Figure 5, with a lower keeper notch 22 adapted to receive the outer end of a spring bolt 23 secured upon the upper edge portion 40 of the ventilator sash 17 for locking the ventilator sash in lowered position. As shown in Figure 6, the inner stop strip 19 may also be provided with a second keeper notch 24 for locking the ventilator sash 17 45 in raised position. The inner stop 19 at the opposite side of the ventilator sash 17 is of the same construction as shown in Figure 7 and is of sufficient depth to receive a tension spring 25 which is secured to 50 the adjacent side of the sliding frame 17 and adapted to hold the same frictionally in adjusted position and also against rattling or vibrating incident to wind pressure.

It is apparent that the ventilating frame 55 may be mounted in the storm sash at any suitable point provided there is a flat pane of glass 16 above the ventilating opening which admits of the upward sliding adjustment of the ventilator frame 17. In 60 Figures 2 and 4 there is shown a slight modification in the location of the ventilator, these figures showing the ventilator mounted at the central portion of a storm sash which is wider than the storm sash 65 shown in Figure 1. In Figure 2 the storm

sash is provided with two vertical sash bars 15 between which the ventilator frame 17 is mounted, and in this instance the inside stop strips 26 may be in the form of flat strips of wood or the like which are secured by nails, or otherwise, to the inner sides of the vertical sash bars 15, as shown in Figure 4. Otherwise, the construction of the parts is identical with that shown in Figures 1 and 3. The stop strip features of the invention is to adapt the inner stop strip to the configuration of the side or central vertical rails or bars of the storm sash so as to provide suitable guide ways and auxiliary stops for the sliding ventilator sash 17 whether it is mounted at one side or at the central portion of the storm window.

70 In use, it is only necessary to retract the bolt 23 and move the sash 17 upwardly to the desired extent when the frictional contact of the spring 25 and the bolt 23 will hold the sash 17 at the desired height. The keeper notches 22 and 24 are adapted to serve as means for positively locking the ventilator sash 17 in either raised or lowered 75 position. It is therefore only necessary to raise the ventilator sash 17 after the inside windows have been opened so as to ventilate the room or interior of the building and obviate the necessity of removing or hinged 80 ly or otherwise mounting the storm window.

85 The bottom rail 13 of the storm sash may have a beveled mortice 27 therein at the upper edge and at its inner side to accommodate the fingers in catching the bottom of the 90 ventilator frame 17 to raise it.

95 It is of course understood that various changes and modifications may be made in the details of construction and design of the several parts which comprise the improved ventilator without departing from the spirit of this invention, the changes and modifications being restricted only by the scope of the following claims.

100 What is claimed is:

1. In combination with a storm sash having transparent panes one arranged above the other and with a lower pane and horizontally dividing sash bar removed, outer and inner stop strips mounted in the storm sash at the opposite sides of the opening from which the pane of glass is removed, and a sliding ventilator frame mounted between the stop strips and against the upper pane of glass therein.

110 2. In combination with a storm sash having panes of glass arranged one above the other and with a lower pane and horizontal dividing sash bar removed, a pair of outer stop strips arranged in the opening and seated against the shoulders from which the pane of glass is removed, a pair of inner stop strips seated against the storm sash frame and providing with the outer stop strips 115 a pair of guide channels, a sliding frame 120 125 130

- fitted in the guide and adapted to move upwardly therein and against the inner side of the upper pane of glass, the inner stop strips extending upwardly in spaced relation to the pane of glass to provide therewith upper extensions of the guide, and a pane of glass mounted in said sliding frame. 5 super-posed pane of glass, a pair of inner stop strips having tongue portions engaging in the opening and shaped to the configuration of the vertical rails of the storm sash and having overhanging flange portions 70 arranged to oppose the outer stop strips and provide therebetween vertical guideways, a frame slidably mounted in the vertical guideways, a pane of glass mounted in said frame, a spring carried at one side of the 75 frame for frictionally holding the same in the guideways, a latch bolt mounted on the frame near the opposite side thereof, the inner stop strips adjacent said bolt having keeper notches therein at various heights 80 adapted to receive the projecting end of the bolt for locking the sliding spring in adjusted position, said inner stop strips extending upwardly in spaced relation to the upper pane of glass to provide continuations of the guideways and for holding the sliding frame against inner side of the pane 85 of glass when the sliding frame is raised.
3. In combination with a storm sash having independent panes of glass therein and with a lower pane of glass and horizontal dividing sash bar removed, a pair of stop strips seated in the storm sash against the shoulders left by the removal of the pane of glass and with the upper ends of the stop strips engaging beneath the edge of the upper pane of glass to support the same, a pair of inner stop strips secured to the storm sash frame at the inner side of the opening and extending upwardly in spaced relation 15 to the upper pane of glass to provide between the outer stop strips, the upper pane of glass and the inner stop strips a pair of vertical guides, a sliding frame fitted in said guides adapted to be raised against the inner 20 side of the upper pane of glass, a pane of glass mounted in the sliding frame, and means for holding the sliding frame in adjusted position. 25
4. In combination with a storm sash having a plurality of panes of glass therein, a lower pane of glass being removed from the storm sash and the lower central horizontal bar being removed beneath the upper pane of glass, a pair of stop strips inserted in the 30 opening in the position of the pane of glass and engaging beneath the upper pane of glass to support the same and to provide a pair of outer stops, a pair of inner stop strips shaped to the configuration of the 35 vertical portions of the storm sash and having inwardly extending flanges providing stops opposed to the outer stops to provide there-between a pair of guides, said inner stop strips extending upwardly in spaced relation to the upper pane of glass to provide 40 a continuation of the guides against the inner side thereof, a ventilator frame slidably mounted in said guides, a pane of glass mounted in the ventilator frame, and a latch 45 bolt carried by the frame near one side thereof, the adjacent inner stop strip extending inwardly across the opposite edges of the sliding frame and provided at spaced points with keeper notches adapted to receive the 50 projecting end of the bolt. 55
5. In combination with a storm sash having a plurality of vertical and horizontal rails and having panes of glass arranged between the rails and with one of the panes 60 of glass at the lower portion of the sash removed, a pair of outer stop strips secured in the opening provided by the removal of the window pane and secured to the frame of the storm window and engaging at their 65 upper ends beneath the lower edge of a 70
- super-posed pane of glass, a pair of inner stop strips having tongue portions engaging in the opening and shaped to the configuration of the vertical rails of the storm sash and having overhanging flange portions 75 arranged to oppose the outer stop strips and provide therebetween vertical guideways, a frame slidably mounted in the vertical guideways, a pane of glass mounted in said frame, a spring carried at one side of the 80 frame for frictionally holding the same in the guideways, a latch bolt mounted on the frame near the opposite side thereof, the inner stop strips adjacent said bolt having keeper notches therein at various heights 85 adapted to receive the projecting end of the bolt for locking the sliding spring in adjusted position, said inner stop strips extending upwardly in spaced relation to the upper pane of glass to provide continuations of the guideways and for holding the sliding frame against inner side of the pane 90 of glass when the sliding frame is raised.
